United States Patent

Des. 242,310
Patented Nov. 16, 1976

242,310

SEAT

Judith W. Fister, 7715 Park Creek Drive,
Centerville, Ohio 45459

Filed May 13, 1975, Ser. No. 577,093

Term of patent 14 years

Int. Cl. D6—01

U.S. Cl. D6—69

Fig. 4

Fig. 5

Fig. 6

FIG. 10

FIG. 11

FIG. 12

FIG. 1 is a front and side perspective view of a seat showing my design in the form of a chair;

FIG. 2 is a frontal perspective view thereof;

FIG. 3 is a perspective view of the rear thereof;

FIG. 4 is a rear elevational view thereof;

FIG. 5 is a top plan view thereof;

FIG. 6 is a bottom plan view thereof;

FIG. 7 is a front and side perspective view of a seat showing my design in the form of a sofa;

FIG. 8 is a frontal perspective view thereof;

FIG. 9 is a perspective view of the rear and one side thereof;

FIG. 10 is a rear elevational view thereof;

FIG. 11 is a top plan view thereof; and

FIG. 12 is a bottom plan view thereof.

I claim:

The ornamental design for a seat, as shown.
